MANIFOLDING PACK

Albert W. Metzner, Dayton, Ohio, assignor to The Standard Register Company, Dayton, Ohio, a corporation of Ohio

Application May 28, 1942, Serial No. 444,857

31 Claims. (Cl. 282—11.5)

This invention pertains to manifolding, and more particularly to an assembly of continuous superposed record strips and interleaved sheets of transfer material, wherein succeeding fresh sets of transfer material are periodically interchanged with used portions thereof automatically at the recording position.

The present manifolding assembly is especially useful in a writing or imprinting apparatus embodying automatic transfer material interchange features and employing a mode of operation of the character disclosed and claimed in copending companion application for Letters Patent Serial No. 444,858 filed May 28, 1942, but is not limited to either the specific mechanism nor the particular steps of the interchange method therein illustrated and described. Cross reference to the aforementioned copending application for patent and the apparatus and process therein illustrated and described is for illustrative purpose only and as an aid to understanding, and not with any intent to unduly limit or restrict the scope or application of the present invention.

In the present instance, sets of transfer material sheets are interleaved at longitudinally spaced intervals between superposed continuous strips of record material. The relative spacing of the transfer sets is somewhat dependent upon the quality of the material and the number of transfer copies which can be made before exhausting the responsive surface of the sheets. As the assembly is advanced through a recording apparatus, the succeeding sets of transfer sheets are temporarily arrested in recording position while advancement of the strips is continued relative thereto. As the succeeding set of transfer sheets approaches the recording position, the preceding set thereof is automatically released and replaced by the succeeding set of transfer sheets. The present invention pertains to the manifolding assembly and the relative arrangement and interconnection of the record strips and transfer sheets for use in carrying out the described method of transfer material interchange.

The object of the invention is to provide an improved manifolding assembly which may not only be economically manufactured, but which will readily enable automatic interchange of fresh transfer material sheets for exhausted sheets thereof in interleaved relation with continuous record strips.

A further object of the invention is to provide a compact assembly of record strips and

interchangeable sets of interleaved transfer sheets of the cartridge type, suitable for insertion into a writing or imprinting apparatus without preparatory manipulation or adjustment.

5 A further object of the invention is to provide an assembly of superposed record strips and interleaved transfer material arranged for automatic periodic interchange of fresh transfer material for used and exhausted portions thereof.

10 A further object of the invention is to provide a manifolding assembly possessing the advantageous structural features and inherent meritorious characteristics herein described.

In the drawings,

15 Fig. 1 is a perspective view of a zigzag folded pack of manifolding material embodying the present invention.

Fig. 2 is a fragmentary plan view of a portion of the assembly.

20 Fig. 3 is a perspective view of one of the transfer sheets removed from the assembly.

Fig. 4 is a perspective view of an extended length of superposed record strips and interleaved transfer material assembled for automatic interchange of succeeding sets of transfer sheets progressively one for another in synchronism with advancement of the strips.

25 Figs. 5, 6, 7 and 8 illustrate modifications of the transfer sheet set.

30 Fig. 9 is a modification of the mode of interconnecting the record strips and manner of ejecting used transfer material.

Like parts are indicated by similar characters of reference throughout the several views.

35 The manifolding assembly forming the subject matter hereof comprises a plurality of superposed strips 1—1 of continuous series connected detachable from stationery which are divisible upon longitudinally spaced transverse

40 weakened division lines 2—2 into separate sheets 3. In the drawings the record strips have been shown as marginally punched for engagement of pin type feeding devices, by which the assembly may be positively advanced and the succeeding

45 forms thereof presented in registering and aligned relation at the recording position. However, such marginal punching and adaptation for pin type feeding devices are non-essential and the present invention is in no way dependent thereon.

50 Disposed between the superposed strips at longitudinally spaced intervals are sets of interleaved transfer sheets 4. The relative spacing of the transfer material sets is dependent somewhat upon the quality of the material and the number

of transfer impressions which can be made therefrom before the transfer surface thereof is exhausted. Ordinarily thirty to fifty copies may be made before it becomes necessary to replace the exhausted material with fresh sheets. Consequently, sets of transfer sheets 4 will be interleaved at relatively long intervals between the thirtieth to fiftieth sets of detachable form lengths 3 of the record strips. Such spacing is mentioned merely as illustrative, and the relation of succeeding sets of transfer sheets may be varied according to conditions of use and the character and quality of the transfer and record materials. The transfer sheets 4 are arranged in offset or overlapping relation with the corresponding form lengths or sections of the strips, as shown in Fig. 2. Each transfer sheet 4 is provided at its trailing edge with an attached relatively stiff reinforcement strip 5, the ends of which are preferably, but not necessarily, offset or shouldered at 6.

The extremities 6 of the strips or bars 5 project laterally beyond the side margins of the record strips 1.

The assembly of superposed record strips and interleaved sheets of transfer material are collectively interconnected closely adjacent to the leading margins of the transfer sheets 4 by wire staples 7. The staples 7 preferably loosely connect the several strips and sheets. That is to say, the staples are preferably not tightly clenched, but enable limited vertical separation of the several plies at the attachment points. Stapling of the assembly may be rapidly and economically performed, but it is to be understood that the invention is not restricted to such mode of interconnection, and other means may be substituted therefor.

The transfer material sheets 4 are of less tensile strength than the record strips 1. They are, however, sufficiently strong to be drawn along with the record strips 1, assisted by the frictional contact of the transfer sheets between superposed record strips without tearing, as the record strips are being advanced toward the recording position.

The assembled superposed record strips and interleaved transfer sheets are preferably zigzag folded into a supply packet, such as shown in Fig. 1. The interleaved transfer sheets being sufficiently long and so placed as to overlap succeeding record forms of the strips, are interfolded with the record strips. The ends 6 of the anchor strips 5 protrude at relatively spaced levels from the sides of the supply pack as they appear in Fig. 1. For storage and shipment these extended ends of the strips 5 may be folded downwardly against the sides of the packet, and as they subsequently advance through the writing machine they will be automatically re-extended.

In a writing or imprinting apparatus, such as that shown in the companion application aforementioned, yielding spring tensioned stops or detents are provided closely adjacent to the path of travel of the assembly into recording position, and in the path of the protruding ends 6 of the strips 5. As the record strips are advanced by suitable strip feeding devices, the ends 6 of the strips 5 engage and are arrested by the stops or detents, the yielding resistance of which is greater than the tensile strength of the transfer material, but less than that of the record strips. The transfer sheets being temporarily held against advancement by engagement of the ends of the

strips 5 with such detents while the record strips continue to advance, the staples are torn from the edges of the transfer sheets. The latter remain stationary in the recording position, while the record strips with the engaged staples continue to advance. After a number of transfer impressions have been made from the arrested transfer sheets, and as the succeeding set of transfer sheets carried by the record strips approaches the recording position, the staple 7 of such succeeding transfer set comes into contact with the anchor strips 5 of the arrested set of transfer sheets 4. The strips and sheets of the succeeding transfer set being loosely engaged by the staple are enabled to separate without tearing to admit the strips 5 therebetween into contact with the staple 7. The record strips being of greater tensile strength than the resistance of the detents, the pull of the strip feeding devices thereon causes the staple 7 to push against the strips 5 of the arrested set of transfer sheets with sufficient force to overcome the resistance of the arresting detents and thereby release the used and exhausted set of transfer sheets. The released set of sheets continue to advance by frictional engagement with the record strips out of the recording position. The ends 6 of the strips 5 of the succeeding set of transfer sheets then engage the spring returned detents and such succeeding set of transfer sheets is arrested in the recording position and are detached from the strips by the tearing loose of the staple 7 as before. Thus, a set of fresh transfer sheets is automatically interchanged for the used set thereof. The interchange operation occurs automatically as often as succeeding sets of sheets are advanced to the recording position and displace the preceding set thereof.

It is not essential that the staple 7 shall be inserted through the transfer material. The transfer material interleaved between the record strips will advance therewith by frictional contact without the aid of the staple. Staples may be inserted through the record strips only in approximate relation with the leading ends of the transfer sheets and serve their purpose of pushing the preceding set of transfer sheets past the arresting detents. While the aforescribed method of automatic interchange is the preferred mode, which is described and claimed in the companion application, it is not necessarily the only method and the present manifolding assembly is not limited thereto.

In Figs. 5 and 6 there appears a modification, wherein, the anchor strips or marginal reinforcements of the several transfer sheets comprising a superposed set thereof are interconnected with each other into a unitary assembly, with only single detent engaging extensions at each side which are common to the entire set of sheets. As therein shown, the transfer sheets are attached to each of a series of spaced interconnected arched bars or strips 5', having therebetween spaces through which the record strips are threaded. The bars 5' are arched to different height, and in Figs. 5 and 6 are offset longitudinally of the record strips in addition to being vertically offset. In Fig. 7 the several interconnected spaced anchor bars 5' are disposed in a vertical plane with only the lowermost thereof extended at 6' for engagement with the arresting detents or stops of the recording apparatus.

In Fig. 8 the several reinforcement strips are each formed with extensions as in the initial

disclosure, except the lowermost strip thereof. The latter is provided with upturned ears 9 which embrace the extensions of the remaining strips of the assembly.

Fig. 9 shows the staple 7 transfixing the record strips only independently of the transfer material, but in operative ejecting engagement with the bars 5 of the preceding set of transfer sheets.

In this modified disclosure the staple is positioned within a shallow marginal notch in the transfer material whereby the staple limits side play and assists in maintaining the alignment of the transfer material with the record strips. However, such limitation of lateral movement is not essential. The transfer sheets being interfolded with the record strips at the transverse division lines of the latter will be effectively held against shifting movement into askew relation while in the supply pack shown in Fig. 1. After leaving the pack the travel movement into recording position is short and ordinarily confined within a writing or recording apparatus. The transfer material is not likely to become disarranged. Therefore, the staples 7 may be located entirely outside the transfer sheets and beyond the leading edges thereof.

The relation of the staples 7 with the strip 5 of the preceding transfer sheet as shown in Fig. 9 is illustrative of the discharge engagement thereof for displacing the exhausted transfer material by pushing it ahead out of recording position in each of the several variations, whatever the relation of the staples to the leading edges of the transfer sheets may be.

In an assembly for use with a pin type feeding apparatus the transfer sheets are disposed relative to the record strips so that the ends of the transfer sheet holder strips 5 will be positioned between succeeding marginal feed holes, and so not interfere with the feeding operation. The pin feed devices are preferably but not necessarily positioned to engage in holes immediately at the rear of the strips 5 of the discharged transfer sheet at the end of the feeding operation by which the transfer sheets are displaced from recording position. This completely frees the exhausted transfer sheets, which may be immediately removed. Otherwise, the ends of the anchor strips 5 being back of or between feeding pins at the completion of the feeding operation, although displaced from recording position, the exhausted transfer material would not be completely released until the succeeding operation.

It is to be understood, however, that the invention is in no way dependent upon pin type feeding mechanism for advancing the record material and alternating the transfer material. Frictional or other forms of feeding mechanism may be employed.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the

preferred form of several modes of putting the invention into effect, and the invention is therefore claimed in any of its forms or modifications within the legitimate and valid scope of the appended claims.

Having thus described my invention, I claim:

1. A manifolding assembly, including a plurality of continuous superposed strips of record material, a series of sets of transfer sheets of less tensile strength than the record strips interleaved at longitudinally spaced intervals therebetween, anchor projections substantially coincident with the trailing edges of the transfer sheets and projecting laterally beyond the margins of the record strips for engagement with sheet arresting devices having yielding resistance greater than the tensile strength of the transfer material and less than that of the record strips for temporarily arresting the transfer material in a recording position, and staples collectively interconnecting the record strips and the interleaved transfer sheets loosely in proximate relation with the leading edges of the transfer sheets, the construction and arrangement being such that the arrested transfer material is periodically automatically released and displaced from the recording position and automatically replaced by substitute transfer material independently of operator intervention.
2. A manifolding assembly including a plurality of superposed record strips and a series of transfer sheets interleaved therebetween at longitudinally spaced intervals, and coupling devices fixedly interconnecting the superposed record strips and interleaved transfer sheets for unison travel movement relative to a recording position, the record strips being of greater tensile strength than that of the transfer material, engaging portions associated with the transfer sheets for temporary engagement with sheet arresting means of greater resistance than the tensile strength of the transfer material and of less resistance than the tensile strength of the record strips, the construction and arrangement being such that the transfer sheets will be torn loose from the record strips and held in recording position while the record strips are advanced relative thereto and ejecting means associated with the succeeding transfer material sheets, effective to automatically release the arrested transfer material to enable further advancement thereof to discharge position in unison with the advancement of the record strips.
3. A manifolding assembly, including a plurality of superposed continuous record strips, a series of transfer sheets interleaved therebetween at longitudinally spaced intervals for unison travel movement thereof relative to a recording position, configurations thereof for effecting temporary arrest of the transfer sheets in the recording position while the record strips are further advanced relative thereto, and means for automatically engaging the arrested transfer sheets with the record strips for further unison movement beyond the recording position, in continuing sequence, the construction and arrangement being such that the transfer sheets are repeatedly employed to transfer succeeding record entries upon the strips while arrested in the recording position and are periodically automatically replaced by succeeding transfer sheets of the series.
4. A manifolding assembly, including a plurality of superposed continuous record strips, a series of sets of transfer sheets interleaved there-

between at longitudinally spaced intervals and interconnected therewith for unison advance movement with the record strips into a recording position, and automatically detachable therefrom when in the recording position, and a coupling device for automatically reengaging the detached transfer sheets with the record strips after a period of independent advancement of the latter to advance the reengaged transfer sheets in unison with the record strips beyond the recording position while a succeeding set of transfer sheets are being advanced in unison therewith into the recording position.

5. A manifolding assembly comprising a plurality of superposed continuous strips of series connected detachable form stationary divisible at longitudinally spaced intervals on transverse weakened lines into a succession of sets of record sheets, a series of separate sets of superposed transfer sheets interleaved at longitudinally spaced intervals between the continuous record strips, including portions on said sets of transfer sheets engageable with detent devices by which the transfer sets are successively temporarily arrested and held in a recording position while the record strips are progressively advanced relative thereto to successively present each of a plurality of detachable record forms successively in registry with the arrested set of transfer sheets in recording position, each set of transfer sheets being constructed and arranged to automatically displace the arrested set of transfer sheets from the recording position preparatory to automatic replacement thereof by the succeeding set of transfer sheets.

6. A manifolding assembly, including a plurality of superposed continuous record strips and a series of interchangeable sets of transfer sheets interleaved between the record strips at longitudinally spaced intervals, each set of transfer sheets being progressively movable with the record strips into recording position, a detent engaging portion associated with each set of transfer sheets for temporarily detaining each advanced set of transfer sheets in a recording position while the record strips are being further advanced independently thereof until a succeeding set of transfer sheets is advanced with the strips into approximate relation with the recording position, and ejector means operative by the advancement of the strips for automatically ejecting the detained transfer sheets from the recording position preparatory to automatic replacement thereof by a succeeding set thereof.

7. A manifolding assembly, including a plurality of superposed continuous record strips, a series of interchangeable sets of transfer sheets interleaved between the record strips at longitudinally spaced intervals, and lateral extensions associated with each set of transfer sheets for releasable engagement with detent means of a recording machine, and ejector means carried by the superposed strips for automatically ejecting each set of transfer sheets from the said detent means after a period of arresting engagement therewith.

8. The combination with a plurality of continuous record strips progressively movable past a recording position, of a series of sets of transfer sheets interleaved therebetween at longitudinally spaced intervals and movable in unison therewith relative to a recording position, detent engaging portions of the transfer sheets for temporarily arresting the transfer sheets in the recording position while the record strips are ad-

vanced relative thereto, and transfer sheet engaging devices carried by the record strips engageable with the arrested transfer sheets upon further movement of the record strips relative to the arrested transfer sheets for effecting further movement of the transfer sheets in unison with the record strips out of the recording position.

9. A manifolding assembly, including a plurality of superposed continuous record strips and a series of sets of transfer sheets interleaved therebetween at longitudinally spaced intervals for unison travel movement relative to a recording position, stops associated with succeeding sets of the transfer sheets successively engageable with detent means by which the sets of transfer sheets are temporarily arrested in the recording position, and coupling means associated with succeeding portions of the record strips by which each arrested set of transfer sheets is automatically engaged with the record strips upon continued advancement of the record strips relative thereto, to further advance the transfer sheets in unison with the record strips beyond the recording position while a succeeding set of transfer sheets advances in unison with the record strips into the recording position.

10. A manifolding assembly of superposed continuous record strips and a series of sets of transfer sheets interleaved therebetween at longitudinally spaced intervals for unison travel movement, and alternately operative transfer sheet arrest and release devices operative by travel movement of the record strips for effecting automatic interchange of succeeding sets of transfer sheets one for the other by continued advancement of the record strips as the sets of transfer sheets successively approach the recording position.

11. A manifolding assembly, including a plurality of superposed continuous record strips and a series of transfer sheets interleaved therebetween at longitudinally spaced intervals for unison travel movement relative to a recording position, the transfer sheets being constructed and arranged for temporary arrest in the recording position while the record strips are advanced relative thereto, and portions of the record strips normally distantly spaced in relation with the arrested transfer sheets constructed and arranged for engagement with the arrested transfer sheets to further advance the transfer sheets in unison with the record strips out of the recording position.

12. A manifolding assembly, including a plurality of superposed continuous record strips and a series of transfer sheets interleaved therebetween at longitudinally spaced intervals for unison travel movement relative to a recording position, the transfer sheets being constructed and arranged for temporary arrest in the recording position while the record strips are advanced relative thereto, a transfer sheet engaging portion carried by the record strips in normally distantly spaced relation with the arrested transfer sheets engageable therewith upon continued advancement of the record strips to automatically displace the arrested sheets from the recording position preparatory to replacement thereof by succeeding transfer material.

13. The combination with a plurality of superposed record strips and a plurality of interchangeable sets of transfer sheets and associated devices operated by travel motion of the record strips for effecting periodic automatic inter-

change of the sets of transfer sheets one for another in interleaved relation with the record strips incident to longitudinal travel movement of the record strips.

14. The combination with a plurality of superposed record strips and a plurality of interchangeable sets of transfer sheets interleaved therewith at longitudinally spaced intervals for unison travel motion, and periodically arrestable in a recording position while the record strips are advanced relative thereto, and associated means operative by travel movement of the record strips for automatically displacing an arrested set of transfer sheets from the recording position preparatory to advancement of a succeeding set of transfer sheets in unison with the record strips into the recording position.

15. A zigzag folded packet of multiple copy stationery, including a plurality of superposed zigzag folded record strips and a plurality of separate sheets of transfer material interleaved between the record strips in relatively spaced folds thereof, coupling means by which the transfer sheets are attached to the record strips for unison travel movement into recording position, from which the sheets are automatically detached upon reaching recording position, the construction and arrangement being such that succeeding portions of the record strips and interfolded transfer sheets are advanced in unison into a recording position wherein the transfer sheets are temporarily arrested until replaced by a succeeding transfer sheet.

16. A manifolding assembly of superposed strips of series connected detachable forms separable on longitudinally spaced transverse weakened division lines and a succession of separate transfer sheets interleaved between the record strips at longitudinally spaced intervals in overlapping relation with certain of the transverse weakened lines of the strips, said transfer sheets being advanced into a recording position by the travel movement of the strips and arrested in such position while the record strips are advanced relative thereto, and ejector means operated by the movement of the strips for automatically displacing the arrested transfer sheets from the recording position preparatory to replacement by succeeding transfer sheets, the construction and arrangement being such that succeeding portions of the record strips and interleaved transfer sheets may be advanced in unison into a recording position wherein the transfer sheets are temporarily arrested while the record strip portions are advanced relative thereto until the arrested transfer sheets are replaced by succeeding transfer sheets.

17. A packet of manifolding material, including superposed record strips interfolded in zigzag formation and a plurality of separate folded transfer sheets interposed within certain relatively spaced folds of the zigzag folded record strips and connected thereto for unison movement, said strips being automatically detachable from the record strips upon reaching a recording position in which they are temporarily arrested, and ejector means carried by the strips for automatically displacing the arrested transfer sheets from recording position, the construction and arrangement being such that the interleaved sheets of transfer material may be successively advanced in unison with the record strips into a recording position wherein each transfer sheet is temporarily arrested until replaced by a succeeding transfer sheet.

18. A manifolding assembly, including superposed continuous strips of series connected detachable record forms separable upon longitudinally spaced transverse weakened division lines, and a succession of separate transfer sheets interleaved between the record strips at longitudinally spaced intervals, detent engaging portions associated with the transfer sheets for temporarily arresting the successive transfer sheets, and staples attaching the leading edges of the transfer sheets to the record strips, the construction and arrangement being such that the interleaved transfer sheets may be successively advanced in unison with the record strips into a recording position wherein each transfer sheet is temporarily arrested until replaced by a succeeding transfer sheet.

19. A manifolding assembly, including superposed record strips a plurality of transfer sheets interposed therebetween at longitudinally spaced intervals for unison advancement through an identical path of travel relative to a recording position, attachment means connecting the transfer sheets to the record strips for unison travel movement, said transfer sheets being automatically detachable from the record strips at the recording position incident to further advancement of the record strips relative thereto, and coupling means for automatically reengaging the detached sheets of transfer material with the record strips for further unison advance movement in unison therewith.

20. A manifolding assembly, including superposed record strips and a series of transfer sheets interleaved between the record strips at longitudinally spaced intervals for advancement successively into recording position in unison with advancement of the strips through the same path of travel, arresting portions on the transfer sheets for temporarily delaying the advancement of the transfer sheets, the strips being capable of further independent advancement relative to the transfer sheet in recording position, and devices for automatically reengaging the delayed transfer sheets with the record strips for further advancement in unison with continued advancement with the strips.

21. A manifolding assembly, including superposed record strips transfer sheets interposed between the record strips at longitudinally spaced intervals, staples transfixing the record strips in proximate relation with the forward margins of the interleaved transfer sheets in relation to their direction of travel through a recording apparatus, and configurations of the transfer sheets for arresting engagement with detent means of a recording apparatus, the construction and arrangement being such that succeeding transfer sheets are temporarily arrested in a recording position while the record strips are advanced relative thereto until ejected therefrom by staples pertaining to succeeding sheets of transfer material.

22. A manifolding assembly, including superposed continuous strips of record material, a series of transfer sheets interposed therebetween at longitudinally spaced intervals, engaging portions associated with succeeding sheets of transfer material engageable with detent means for temporarily arresting the succeeding transfer sheets in a recording position, and ejector means carried by the record strips at longitudinally spaced intervals for automatically releasing the arrested transfer material sheets preparatory to replacement by succeeding transfer sheets.

23. A manifolding assembly, including superposed continuous strips of record material, a series of sheets of transfer material interleaved between the record strips at longitudinally spaced intervals and advanced therewith relative to a recording position, means enabling the temporary arrest of succeeding transfer sheets in the recording position while the record strips are advanced relative thereto, and transfer sheet release means automatically operable by the advancement of the record strips for intermittently releasing the arrested transfer sheets preparatory to automatic replacement thereof by succeeding transfer sheets.

24. A manifolding assembly, including superposed continuous record strips and a succession of transfer sheets interleaved therebetween, attachment means fixedly securing the transfer sheets to the record strips at longitudinally spaced intervals, the transfer sheets being of less tensile strength than the record strips, said transfer sheets being adapted for temporary engagement with detent means by which the transfer sheets are held in a recording position while the record strips are automatically detached therefrom and advanced relative thereto, the construction and arrangement being such that upon movement of the record strips while the transfer sheet is held in arrested position the attachment means is torn loose from the transfer sheets.

25. A manifolding assembly, including superposed continuous strips of record material and a series of transfer material interleaved between the record strips at longitudinally spaced intervals, engaging portions associated with the transfer sheets for automatically effecting temporary arrest and detention of succeeding transfer sheets in a recording position, and release devices carried by the record strips at longitudinally spaced intervals effective to automatically release previously arrested transfer sheets preparatory to automatic replacement thereof by succeeding sheets of the series.

26. A manifolding assembly, including a plurality of superposed continuous record strips for progressive advancement past a recording position, sheets of transfer material interposed therebetween at longitudinally spaced intervals, and staples interconnecting the leading edges of the transfer sheets with the record strips for unison advancement therewith.

27. A manifolding assembly, including a plurality of superposed continuous record strips for progressive advancement past a recording position, sheets of transfer material interposed there-

between at longitudinally spaced intervals, the transfer sheets being attached to the record strips at their leading edges for unison advancement therewith.

5 28. A manifolding assembly, including a plurality of superposed continuous record strips for progressive advancement past a recording position, sheets of transfer material interposed therebetween at longitudinally spaced intervals, the latter being subject to temporary delay while the record strips are advanced relative thereto, and sheet engaging devices carried by the strips and engageable with the delayed transfer sheets for further advancing the latter in unison with the advancement of the strips.

10 29. A manifolding assembly, including a plurality of superposed continuous record strips for progressive advancement past a recording position, sheets of transfer material interposed therebetween at longitudinally spaced intervals, and coupling means connecting the transfer sheets with the record strips for unison advancement into a recording position and operative to automatically temporarily release the transfer sheets from the record strip at such position and thereafter reengage the transfer sheets and record strips for continued unison advancement.

15 30. An assembly of superposed continuous record strips, and a plurality of transfer sheet units interleaved between the strips at longitudinally spaced intervals for unison advancement from a source of supply to a record receiving position, each transfer sheet unit being constructed and arranged to be automatically arrested in record receiving position while the record strips continue to advance relative thereto, each transfer sheet unit being further constructed and arranged to effect automatic displacement of a previously arrested transfer sheet unit from the recording position for automatic replacement thereof by the succeeding unit.

20 31. A manifolding assembly, wherein superposed continuous record strips, having transfer sheets interleaved therebetween at longitudinally spaced intervals are advanced in unison toward a recording position, including arresting devices associated with the transfer sheets releasably engageable with stop means to temporarily arrest the transfer sheets in sequence in the recording position, and release means associated with the succeeding transfer sheets for automatically disengaging the preceding transfer sheet from the stop means for removal from the recording position to enable the succeeding sheet to occupy the position vacated by the preceding transfer sheet.

25 ALBERT W. METZNER.
